(57) **CLAIM**

The ornamental design for a mount for packaging, as shown and described.

DESCRIPTION

FIG. 1 is a perspective view of the top, front and right side of a mount for packaging showing my new design;

FIG. 2 is a front view thereof, the rear view being identical thereto;

FIG. 3 is a right side view thereof, the left side view being identical thereto;

FIG. 4 is a top plan view thereof;

FIG. 5 is a bottom view thereof; and,

FIG. 6 is a reference view showing the article in an environment.

The broken lines in the Figures are for illustrative purposes only and form no part of the claimed design.
